UNITED STATES PATENT OFFICE.

EDWARD H. CLAY, OF CHAGRIN FALLS, OHIO.

CARBURETER FOR EXPLOSIVE-ENGINES.

SPECIFICATION forming part of Letters Patent No. 770,559, dated September 20, 1904.

Application filed June 26, 1903. Serial No. 163,173. (No model.)

To all whom it may concern:

Be it known that I, EDWARD H. CLAY, a citizen of the United States, residing at Chagrin Falls, in the county of Cuyahoga and State of Ohio, have invented a certain new and useful Improvement in Carbureters for Explosive-Engines, of which the following is a full, clear, and exact description, reference being had to the accompanying drawings.

10 My invention relates to improvements in carbureters; and it consists in the construction and combination of parts hereinafter shown, described, and claimed, whereby the operator may increase or diminish at will the 15 supply of the explosive mixture formed and discharge for use without substantially changing the relative proportions of the constituent parts of said explosive mixture.

Referring to the drawings, Figure 1 is a vertical section through the device. Fig. 2 is an elevation of the valve-casing, and Fig. 3 is an elevation of the needle-valve and the stem to which it is attached.

Referring to the parts by letters, A represents a casing containing a mixing-chamber A', provided with a hydrocarbon-inlet α^2 , an air-inlet α , and a mixture-outlet α^3 . The mixture passes through this outlet into a receiving-chamber A², from which it passes through the opening α^4 to the engine or other mechanism in which it is utilized. The outlet α^3 is surrounded by a tapered valve-seat α^5 , for which the conical valve B is provided. The hydrocarbon-inlet α^2 is directly opposite the opening α^3 , and a needle-valve D projects into said inlet α^2 , said needle-valve being rigidly but adjustably secured to the valve B, so that both must move simultaneously. This needle-valve has a stem d , which passes through and screws into a hole b' , extending through the valve B and its stem b , and projects from the outer end of said stem, so that it may be operated for the purpose of adjustment. The stem b of the valve projects through the cap E of the casing, and to said projecting end an operating-lever G is secured. A spring H surrounds the stem and lies between the valve and the cap E and exerts its force to move said valve toward its seat. The complete closing 50 of the valve is prevented, however, by the

engagement of the lever G with the cap. The valve must always be opened far enough to permit the flow through the opening α^3 of the minimum volume of the mixture required.

When the valve B is as nearly closed as possible, the needle-valve is adjusted so that the effective size of the opening α^2 is such as to admit the proper proportion of hydrocarbon for the minimum volume of mixture which can pass through the opening α^3 . The two valves B and D are so shaped that the effective size of the openings α^2 and α^3 will be proportionately increased or diminished by the simultaneous movement of said valves. The lever G projects out through a notch e' in a flange e on the cap E, which notch has one inclined or cam surface e' , with which the lever G engages. By turning this lever in one direction, so that it rides up this cam-surface, the valve will be drawn away from its seat, and the needle-valve D will at the same time be moved so as to proportionately enlarge the opening α^2 . Thus by operating this lever the volume of the mixture formed and allowed to flow may be increased or diminished; but the character of the mixture will remain substantially unchanged. It will be understood that this mechanism is wholly independent of the valves which must be employed to control the periodic admission of the explosive mixture to the explosive-chamber of an engine. The present invention affords means for varying the volume of the mixture allowed to flow toward an engine and provides for the formation of the mixture as fast as required; but it preserves the substantial uniformity of the mixture in respect to the proportions of air and gas therein. If a liquid hydrocarbon is admitted through the inlet α^2 , it is discharged against the conical valve B, on the surface of which it spreads, so as to be easily vaporized by the air flowing across the said surface.

Having described my invention, I claim—

1. In a carbureter, the combination of a casing containing a mixing-chamber having an air-inlet, a hydrocarbon-inlet and a mixture-outlet formed in line with said hydrocarbon-inlet and in the opposite wall of the mixing-chamber with a conical valve for said outlet, 95

a needle-valve which enters the hydrocarbon-inlet and has its stem screwed through said valve, and mechanism under the control of the operator for moving said valve, substantially as described.

2. In a carbureter, the combination of a casting containing a mixing-chamber having an air-inlet, a hydrocarbon-inlet, and a mixture-outlet, with a conical valve for said outlet having a stem which extends out of said casting, a spring moving said valve in one direction, a handle secured to said stem, a cam-surface with which said handle engages, and a needle-valve which enters the hydrocarbon-inlet and is connected with the conical valve, substantially as described.

3. In a carbureter, the combination of a casting containing a mixing-chamber having an air-inlet, a hydrocarbon-inlet, and a mixture-outlet formed in line with said hydrocarbon-inlet and in the opposite wall of the mixing-chamber, with a valve for said outlet, a spring

pressing said valve toward its seat, and a needle-valve which screws through the mixture-outlet valve and enters the hydrocarbon-inlet, substantially as described.

4. In a carbureter, the combination of a casting, containing a mixing-chamber having an air-inlet, a hydrocarbon-inlet and a mixture-outlet, a valve for closing said mixture-outlet, a needle-valve adjustably secured within said mixture-valve and being operated in unison therewith, said valves retaining the same proportion of air to hydrocarbon as originally adjusted, said valves being adapted to be operated by the suction caused by the piston in the cylinder.

In testimony whereof I hereunto affix my signature in the presence of two witnesses.

EDWARD H. CLAY.
